UNITED STATES PATENT OFFICE

112,984

DESIGNED FOR A STEMMED GOBLET

Gerard S. Bryce, Mount Pleasant, Pa., assignor
to Bryce Brothers Company, Mount Pleasant,
Pa., a corporation of Pennsylvania

Application November 26, 1938, Serial No. 81,388

Term of patent 14 years

To all whom it may concern:

Be it known that I, Gerard S. Bryce, a citizen of the United States and residing at Mount Pleasant, in the county of Westmoreland and State of Pennsylvania, have invented a new, original, and ornamental Design for a Stemmed Goblet, of which the following is a specification, reference being had to the accompanying drawing, forming a part thereof, wherein the figure is a front

view of a stemmed goblet, of conventional circular contour throughout, illustrating my new design.

It is to be understood that my new design may be applied to a complete line of stemmed ware.

I claim:

The ornamental design for a stemmed goblet, as shown and described.

GERARD S. BRYCE.
